United States Patent Office

Des. 233,830

Patented Dec. 3, 1974

233,830

PACKAGE OF SPOONS OR THE LIKE

Samuel R. Davis, Jr., and Harry A. Watson, Federalsburg, Md., assignors to Maryland Plastics Incorporated, Federalsburg, Md.

Filed Sept. 13, 1972, Ser. No. 288,696

Term of patent 14 years

Int. Cl. D9—99

U.S. Cl. D9—193

FIG. 1 is a plan view showing our new design, a package of spoons or the like;

FIG. 2 is a side elevational view thereof;

FIG. 3 is an end elevational view thereof; and

FIG. 4 is a fragmentary perspective view thereof. The side opposite the side shown is plain.

We claim:

The ornamental design for a package of spoons or the like, substantially as shown and described.
